UNITED STATES PATENT OFFICE

2,447,308

PROCESS FOR IMPROVING THE COLOR OF
SURFACE-ACTIVE AGENTS

Leland James Beckham, Geddes, and William Alfred Fessler, Camillus, N. Y., assignors to Allied Chemical & Dye Corporation, a corporation of New York

No Drawing. Application October 12, 1943,
Serial No. 505,960

7 Claims. (Cl. 260—504)

1

This invention relates to an improvement in certain processes for preparing water-soluble surface-active compositions which are suitable for use as detergents, wetting agents, emulsifying agents, dispersing agents, washing agents or cleansing agents, from olefinic hydrocarbon mixtures, especially those obtained from petroleum and other mineral sources.

As disclosed in United States Patent No. 2,265,993 of December 16, 1941, surface-active compositions can be advantageously obtained from hydrocarbon mixtures containing olefinic hydrocarbons having 10 or more carbon atoms, by treatment of such mixtures with a nitrosyl halide to convert the olefins into their nitrosyl halide addition products, followed by reaction of the addition products with an aqueous sulfite to convert the addition products into a complex mixture of surface-active hydrocarbon derivatives containing water-solubilizing groups, especially sulfonate and sulfamate groups. The products of this process comprise mixtures of sulfonated ketones, sulfonated amines, sulfonated alkylidene sulfamates, sulfonated alkyl sulfamates, and bisulfite addition products of sulfonated alkylidene sulfamates.

Application, Serial No. 427,345, filed January 19, 1942, of Herman A. Beekhuis, Jr., discloses a modification of the process of the aforesaid patent in which nitrosyl chloride containing nitrogen tetroxide or nitrogen trioxide is employed in the initial treatment of the olefinic hydrocarbon mixtures.

U. S. P. 2,313,719 of March 16, 1943, to one of us discloses another process for making similar surface-active compositions from the olefinic hydrocarbon mixtures, in which the olefinic hydrocarbon mixtures are reacted with nitrogen tetroxide or nitrogen trioxide to convert the olefinic hydrocarbons contained in the mixtures to nitroso nitrates or nitroso nitrites, and the addition products obtained are reacted with an aqueous sulfite.

The products prepared by the aforesaid processes are designated herein as "nitrosation-sulfitation products," and the nitrosyl halide or nitrogen oxides employed in the initial step of the processes are termed herein "nitrosating agents." The olefinic hydrocarbon mixtures employed as starting materials in the processes are preferably obtained from petroleum oils.

It has been found that olefinic hydrocarbon mixtures of the aforesaid type contain chromogenetic, or color-forming, constituents which, regardless whether they are colorless or colored in themselves, form colored bodies when subjected

2

to the nitrosation-sulfitation process of the aforesaid patents and application; so that when such olefinic hydrocarbon mixtures, and especially cracked or dehydrogenated petroleum fractions, are subjected to a nitrosation-sulfitation process, surface-active compositions are formed containing colored impurities which seriously impair the value of the products. For instance, in the textile industry, products which are contaminated with colored impurities are unsuitable for washing white wool; and for household purposes, a colored detergent generally meets with considerable sale resistance because of its appearance. In carrying out the process of U. S. P. 2,265,993, it has been observed, furthermore, that considerable variation in the depth of color of the surface-active compositions results upon subjecting olefinic hydrocarbon mixtures from various sources to the nitrosation-sulfitation treatment. It has been found for instance that marked differences exist in the content of chromogenetic substances in olefinic hydrocarbon mixtures derived, by cracking or dehydrogenation, from petroleum fractions of different geographical origin, as well as from different fractions of similar crude petroleum oils. While some improvement in the color of the resulting surface-active materials can be effected by judicious selection of the olefinic raw material, such selection is generally inconvenient and uneconomical.

We have now discovered that the color of surface-active compositions prepared in the aforesaid manner, particularly by processes involving nitrosation with nitrosyl chloride, from hydrocarbon mixtures comprising olefins and derived from a mineral source, can be reduced to a small fraction of its normal value (in terms of relative light-absorbing power), by subjecting the olefinic hydrocarbon mixture which serves as the raw material for the nitrosation-sulfitation process to extraction, before treatment thereof with the nitrosating agent, with an incompletely miscible polar solvent of the type hereinafter identified. Moreover, we have found that the aforesaid improvement in color of the surface-active compositions can be achieved, without removing more than a minor portion of the unsaturated constituents of the original hydrocarbon mixture, by carrying out the extraction with a limited amount of said solvent; for example, an amount not exceeding that which would reduce the proportion of olefinic constituents in the raffinate, in terms of molecular equivalents of mono-olefins, to 85 per cent of the proportion of olefinic constituents, in terms of molecular equivalents of mono-

olefins, present in the original hydrocarbon mixture. We have also discovered that the extraction treatment according to the invention removes not only the chromogenetic constituents of the hydrocarbon mixtures but also most of the constituents which form insoluble gum during the nitrosation.

We have further found that furfural, ethylene glycol monomethyl ether, and liquid sulfur dioxide have exceptional extractive powers for the chromogenetic constituents of such mixtures and especially those composed mainly of hydrocarbons containing 14 to 23 carbon atoms, as hereinafter more fully described.

It was well known heretofore to extract petroleum fractions with selective solvents of various types including the aforesaid polar solvents, for the purpose of increasing their resistance to oxidation, to increase their viscosity or lubricating value, or to remove colored impurities. It was generally recognized that such extraction treatments were effective for removal of at least part of the unsaturated constituents and cyclic (e. g., naphthenic or aromatic) constituents of complex hydrocarbon mixtures, leaving the paraffinic constituents in a more concentrated form in the residue or raffinate phase.

It was not known, however, that the chromogenetic constituents are selectively dissolved by polar solvents of the type referred to herein. The nature of the chromogenetic constituents of the hydrocarbon mixtures serving as raw materials for the aforesaid nitrosation-sulfitation processes is not known. Furthermore, it was not known that chromogenetic constituents could be extracted by said solvents without substantially altering the degree of unsaturation of the hydrocarbon mixtures, in the case of such olefinic hydrocarbon mixtures as petroleum fractions obtained by cracking processes. It was therefore surprising to find that the preliminary extraction of the hydrocarbon mixture in accordance with the present invention would so modify the hydrocarbon mixture that nitrosation-sulfitation products of greatly improved color could be obtained without interfering with the operation of the nitrosation-sulfitation process. Moreover, the amount of surface-active agents, obtained per unit weight of olefinic hydrocarbons contained in the hydrocarbon mixture subjected to nitrosation and sulfitation, is in most cases increased substantially by the preliminary solvent extraction according to this invention, often by as much as 10% to 15%.

The process according to this invention comprises extracting a hydrocarbon mixture containing olefinic hydrocarbons and derived from a mineral source, with a polar solvent which is incompletely miscible therewith and which is characterized by preferential dissolving power for the more polar constituents of cracked petroleum, by bringing the solvent and the hydrocarbon mixture into intimate contact, separating the solvent extract phase from the undissolved hydrocarbon or raffinate phase, and reacting the olefins contained in the raffinate phase successively with a nitrosating agent of the type disclosed in the patents and application discussed above, but preferably with a nitrosyl halide, and then with an aqueous solution of a water-soluble sulfite. Preferably any residual solvent dissolved in the raffinate phase is eliminated from the resultant hydrocarbon mixture, before treatment thereof with the nitrosating

agent, and any insoluble gum formed during the nitrosation treatment is preferably separated from the resulting reaction mixture before treatment thereof with the aqueous solution of the water-soluble sulfite.

If desired, in order to insure utmost utilization of the olefinic components of the original hydrocarbon mixture, the portion thereof which is removed by extraction and contained in the solvent extract phase, including the chromogenetic constituents, can be processed in the same manner as the purified portion contained in the raffinate phase, for example by subjecting it to a nitrosation-sulfitation treatment. While the resulting nitrosation-sulfitation products are highly colored, they possess valuable surface-active properties in aqueous solution, such as wetting, emulsifying and cleansing power; so that they can be used to advantage where these properties are desired but where the color of the composition is of no consequence.

The improved process of this invention can be advantageously applied generally to olefin-containing hydrocarbon mixtures derived from mineral sources; for instance, petroleum hydrocarbons obtained by cracking, dehydrogenating or oxidizing petroleum fractions, and synthetic hydrocarbon mixtures obtained by catalytic hydrogenation of carbon oxides or by catalytic hydrogenation of coal. The process is especially advantageous for treatment of such hydrocarbon mixtures obtained by cracking or dehydrogenating petroleum fractions. In order to form surface-active compositions the olefins contained in such mixtures generally contain 10 to 30 carbon atoms. However, the present process is preferably applied to olefinic hydrocarbon mixtures composed mainly of hydrocarbons containing 14 to 23 carbon atoms, i. e., containing not more than 15% by weight of hydrocarbons having more than 23 or less than 14 carbon atoms. The best results, in so far as improvement in color of the surface-active agents and convenience and economy of operation are concerned, are obtained with hydrocarbon mixtures containing no substantial proportion (not more than 15% by weight) of hydrocarbons other than those having 14 to 23 carbon atoms. Such mixtures have been found to yield not only the most effective surface-active materials but also to respond most readily to the improved treatment of this invention. The presence of excessive proportions of hydrocarbons of less than 14 carbon atoms in the hydrocarbon mixture to be extracted tends to cause dilution of the selective solvent employed in the extraction, rendering it less selective for removal of chromogenetic materials and rendering recovery of the solvent by distillation of the extract difficult; while the presence of excessive amounts of hydrocarbons of more than 23 carbon atoms tends to increase inordinately the amount of solvent required to effect a given improvement in the color of the surface-active agents produced.

The selective solvents employed according to this invention are polar compounds, containing nitrogen, oxygen or sulfur, which are partly miscible with the hydrocarbon mixture to be treated, and which are characterized by preferential dissolving power for the more polar constituents of cracked petroleum—that is, they have greater dissolving power for the more polar and polarizable constituents of cracked petro-

leum (such as, compounds containing oxygen, sulfur or nitrogen, aromatic hydrocarbons, and conjugated diolefins) than for the less polar and polarizable constituents (such as, paraffins and cycloparaffins). The preferred solvents are chosen on the basis of their selectivity in extracting the chromogenetic constituents of the olefinic hydrocarbon mixtures to be processed. By way of contrast with the extraction processes heretofore known, in the extraction treatment of this invention, the purpose is to avoid, as far as possible, the removal of the unsaturated constituents of the original hydrocarbon mixture, while eliminating the chromogenetic constituents, whether saturated or unsaturated. In addition to their selective extracting power for chromogenetic materials, other properties of the solvents are of importance: for example, they are preferably stable or inert under the extraction conditions and under the conditions of solvent recovery; their specific gravity differs substantially from that of the hydrocarbon mixtures to be extracted, being for instance greater than 0.95 or less than 0.75, in order to facilitate gravity separation of the raffinate from the solvent extract; and their boiling points preferably differ from the boiling range of the hydrocarbons contained in the raffinate and also in the solvent extract, being for instance less than 200° C., in order to facilitate solvent recovery by distillation.

A considerable number of solvents have been found suitable for removing chromogenetic constituents from hydrocarbon mixtures according to this invention, especially where olefinic hydrocarbon mixtures in which the hydrocarbons contain from 14 to 23 carbon atoms are used as raw materials. They include esters (such as methyl lactate and methyl formate), alcohols (such as, diethylene glycol, furfuryl alcohol, ethanolamine, diethanolamine, or ethylene chlorohydrin); ethers (such as beta-beta'-dichloroethyl ether and ethylene glycol monomethyl ether), aldehydes (such as furfural), hydroxy aromatic compounds (such as phenol or cresol), nitro compounds (such as nitro-methane or nitro-benzene), cyclic nitrogen bases (such as morpholine or pyridine), alkylamines (such as methylamine or ethylene diamine), and liquid sulfur dioxide. Sulfur dioxide is suitable, for instance at 50° C. for treatment of olefinic petroleum fractions, the operation being carried out at this temperature under superatmospheric pressure. Methyl lactate, ethylene chlorohydrin, and nitro-methane can be used at temperatures from 30° to 100° C. However, ethylene chlorohydrin tends to corrode metal equipment; nitro-methane is explosive at elevated temperatures; and methyl lactate tends to decompose with formation of lactides during distillation for its recovery. Solvents such as nitro-benzene, phenol, and beta-beta'-dichloroethyl ether, in which hydrocarbons within the aforesaid range are excessively soluble, can be used under conditions favoring reduction of the solubility of hydrocarbons therein, e. g., by maintaining relatively low temperatures or by introducing minor proportions of antisolvents in the extraction. Morpholine, pyridine and methyl formate can be used at temperatures below 30° C. or in the presence of an antisolvent.

We have found that furfural, ethylene glycol monomethyl ether (methyl Cellosolve), and liquid sulfur dioxide are preferable for the purposes of the present invention from the standpoint of specific gravity, boiling point, stability, and selec-

tivity for the chromogenetic constituents of olefinic hydrocarbon mixtures containing mainly hydrocarbons from 14 to 23 carbon atoms. Furfural is preferred to ethylene glycol monomethyl ether (methyl Cellosolve) because of its somewhat greater selectivity for chromogenetic constituents of the hydrocarbon mixtures, and its lower cost; and to liquid sulfur dioxide because of the necessity of using a closed system under pressure, at optimum operating temperatures in order to maintain the sulfur dioxide in the liquid phase. Preferably, dry (i. e., substantially free of moisture) furfural and ethylene glycol monomethyl ether are used, since the presence of moisture reduces the dissolving power of the solvents for constituents of the hydrocarbon mixture, and in the case of furfural tends to lower its selectivity in removing chromogenetic materials. Thus, if moisture is present in substantial amount in either of these solvents, it increases the amount of solvent required to effect a given degree of purification, and in the case of furfural correspondingly lowers the yield of purified material of a given degree of purity.

The relative quantities of the solvent and of the olefinic hydrocarbon mixture introduced into the extraction zone, the temperature of the extraction and the intimacy and duration of contact of the liquids in the extraction zone are regulated so that only a part of the unsaturated, or more specifically the olefinic, constituents of the original hydrocarbon mixture are removed in the form of a solvent-extract. The quantity of the solvent employed in the extraction is preferably limited to an amount yielding a raffinate in which the hydrocarbons contain a proportion of olefinic constituents (in terms of molecular equivalents of mono-olefins) which does not differ from the proportion of olefinic constituents in the original hydrocarbon mixture (in terms of molecular equivalents of mono-olefins) by more than 15% of its original value. The raffinate phase, consisting mainly of undissolved hydrocarbons is separated from the solvent extract, preferably by a gravity separation. The solvent which is dissolved in the raffinate is then removed, e. g., by distillation, especially under reduced pressure, or by extraction with another solvent in which the hydrocarbons are insoluble.

The raffinate is then processed to produce a nitrosation-sulfitation product, preferably in the manner described in U. S. P. 2,265,993, by reaction with a nitrosyl halide and subsequent sulfitation of the nitrosation product with an aqueous sulfite solution, or if desired, the process of U. S. P. 2,313,719 or U. S. patent application Serial No. 427,345 of January 19, 1942. The unreacted hydrocarbons are removed from the sulfitation mixture and the latter is evaporated to dryness to obtain water-soluble surface-active materials in the form of a composition suitable for marketing.

When ethylene glycol monomethyl ether or furfural is used as the extraction solvent, it has been found advantageous to employ a countercurrent extraction column equivalent to 7 to 15, and preferably about 10, theoretical plates. The hydrocarbon mixture or raffinate preferably forms the continuous phase, and the solvent or extract, the discontinuous phase. The temperature can be maintained at 0° to 70° C., and preferably at 25° to 50° C., during the extraction; optimum results are obtained, however, at temperatures of 25° to 30° C. The relative rates of introduction of the solvent and of the hydro-

carbon mixture can be adjusted within the range of about 2.5:1 to about 5:1, and preferably about 3:1. Lower ratios of the rate of flow of solvent to hydrocarbon mixture, for instance as low as 0.5:1 by weight, have been found to improve the color of the detergent compositions to a considerable extent, however.

Liquid sulfur dioxide can be employed in a similar manner in a closed apparatus under superatmospheric pressure, for example, at about 50 to 52 lbs. per square inch gauge pressure, at a temperature of about 30° C. or at 105 lbs. per square inch gauge pressure at a temperature of about 50° C.

After extraction is complete, the raffinate is usually treated for removal of the residual polar solvent contained therein; for instance, by distillation or by extraction with another solvent (e. g., water) which is substantially immiscible with the hydrocarbons but is to some extent a solvent for the extracting agent. The solvent may be similarly recovered from the solvent extract and recycled to the extraction process.

The raffinate fraction, containing the major portion of the olefins present in the original hydrocarbon mixture but from which chromogenetic materials have been removed, is subjected to treatment with a nitrosating agent, preferably a nitrosyl halide, and especially nitrosyl chloride, in order to convert the olefins contained therein into nitrosation products, especially their nitrosyl halide addition products. The temperature can be maintained from -20° C. to 80° C., but is preferably held at not more than 35° C. From about 1.25 to 4, and preferably 2.5 to 3, mols of nitrosyl chloride are employed per mol equivalent of mono-olefin in the hydrocarbon mixture. After removing excess nitrosyl chloride by aeration, the mixture is allowed to settle and the liquid portion thereof preferably decanted from the insoluble gummy substance formed during the nitrosyl halide treatment.

The decanted reaction mixture is then sulfited by heating to a temperature of about 85° C. with an aqueous alkali metal sulfite solution (e. g., about 2.5 to 5 mols and preferably 4 mols for each mol of original mono-olefin) containing a water-soluble organic solvent, e. g., isopropyl alcohol (from 1 to 15 mols and preferably about 3 mols per mol of mono-olefin equivalent). The reaction requires about 4 to about 16 hours, depending upon the concentration of the nitrosyl halide addition products in the hydrocarbon mixture, lower concentrations requiring a longer reaction period. When the reaction is complete the unreacted oil is removed by decantation and the portion emulsified in the aqueous part of the reaction mixture is removed, for instance, by extraction with a low-boiling hydrocarbon fraction, such as petroleum naphtha or heptane, in the presence of a minor proportion of isopropyl alcohol. The aqueous solution is separated from the unreacted hydrocarbons by stratification and decantation, and the isopropyl alcohol removed from the solution by distillation. The organic carbon content of the solution is advantageously standardized by addition of inorganic salts, such as sodium sulfate or sodium sulfite, and the solution is evaporated to dryness in order to obtain the surface-active composition in dry form.

Upon determining the light-absorbing power or depth of color of an aqueous solution of the product, for instance by means of a comparative photometer, the light absorption is generally about $\frac{1}{4}$ to about $\frac{1}{8}$ of that shown by a product pre-

pared from the same petroleum stock but without the preliminary solvent extraction of the present invention.

The hydrocarbon fraction contained in the solvent extract phase, including the chromogenetic components of the original hydrocarbon mixture, preferably after removal of the solvent, can be converted into sulfonate mixtures; for example in the same manner as the raffinate fraction, or by direct sulfonation as disclosed for instance in U. S. P. 2,179,174. Mixtures of water-soluble sulfonates can be obtained in this manner which are relatively highly colored but which nevertheless possess surface-active properties in aqueous solution. In this way, utmost utilization of the olefinic components of the original hydrocarbon mixture can be secured.

The process of this invention is illustrated by the following examples in which temperatures are in degrees centigrade and parts and percentages are by weight.

Example 1.—The following hydrocarbon mixtures were each extracted in a countercurrent extraction zone substantially equivalent to 10 theoretical plates at a temperature of 25° to 30° with furfural, the amounts of the furfural and of the hydrocarbon mixture introduced into the reaction zone being in the ratio of 3:1 (by weight):

30 A. A cracked petrodatum fraction composed mainly of hydrocarbons containing from 14 to 23 carbon atoms (with 7.2% of higher molecular hydrocarbons) the average carbon content of the olefins contained therein being 17.4 carbon atoms per molecule, and the mixture including the molecular equivalent of 68.5% of mono-olefins.

B. A cracked Pennsylvania cylinder stock fraction, composed mainly of hydrocarbons containing 14 to 23 carbon atoms (with 9.6% of higher molecular weight hydrocarbons) the average carbon content of the olefins contained therein being 17.7 carbon atoms per molecule, and the mixture including the molecular equivalent of 49.6% of mono-olefins.

45 C. A dehydrogenated mineral seal oil fraction, composed of hydrocarbons containing from 14 to 21 carbon atoms, the average carbon content of the olefins contained therein being 17.0 carbon atoms per molecule, and the mixture including the molecular equivalent of 11% of mono-olefins.

D. A dehydrogenated Pennsylvania gas oil fraction, composed mainly of hydrocarbons of 14 to 23 carbon atoms (with 3.5% of higher molecular weight hydrocarbons) the average carbon content of the olefins contained therein being 18.2 carbon atoms per molecule, and the mixture including the molecular equivalent of 11% of mono-olefins.

E. A fraction of a cracked topped Louisiana crude petroleum, composed mainly of hydrocarbons having from 14 to 23 carbon atoms (with about 13.3% of higher molecular weight hydrocarbons), the average carbon content of the olefins contained therein being 18 carbon atoms per molecule and the mixture including the molecular equivalent of 13.3% of mono-olefins.

F. A fraction of a cracked topped Louisiana crude petroleum, similar to fraction E, but composed of hydrocarbons containing from 14 to 23 carbon atoms and containing no substantial percentage of hydrocarbons of more than 23 carbon atoms, the average carbon content of the olefins contained therein being 17.7 carbon atoms per molecule, and the mixture including the molecular equivalent of 14.1% of mono-olefins.

75 G. A fraction of a cracked Louisiana paraffin

distillate, composed of hydrocarbons containing 14 to 23 carbon atoms (with about 4.4% of higher molecular weight hydrocarbons), the average carbon content of the olefins contained therein being 17.0 carbon atoms per molecule, and the mixture including the molecular equivalent of 21.0% of mono-olefins.

The difference in density of the two liquid phases was utilized to maintain countercurrent flow in the extraction zone, and to effect separate recovery of a solvent extract phase and a raffinate phase. The furfural contained in the raffinate phase recovered from each of the mixtures was removed by distillation and the equivalent olefin content of the residual raffinate was determined. The percentage of each of the hydrocarbon fractions recovered in the form of a raffinate, and the percentage of the mono-olefin equivalents originally contained in each of the fractions, recovered in the raffinate, were as follows:

	Raffinate Yield	Olefin Yield
	Percent	Percent
A	75	75
B	69	69
C	85	80
D	85	79
E	74	76
F	77	70
G	67	58

In order to prepare the nitrosyl chloride addition products of the olefins, quantities of each of the raffinate mixtures, as well as of the original hydrocarbon mixtures, containing in each case the substantial equivalent of one mol of mono-olefin, were gradually mixed with 165 to 195 parts of liquid nitrosyl chloride (2.5 to 3 mols) and the mixtures were agitated and cooled to maintain the temperature below 35°. The time for completion of the addition reaction varied from about 5 to about 9 hours. Upon completion of the reaction, the reaction mixtures were aerated to remove unreacted nitrosyl chloride, and the insoluble gum which was formed by the reaction was allowed to settle. The liquid portion of each reaction mixture was decanted and the amount of insoluble gum determined. The initial quantities of the hydrocarbon mixtures and of the raffinate mixtures and the quantity of gum formed in each case were as follows:

	Quantity of Hydrocarbon reacted with NOCl		Quantity of Gum Deposited by reaction with NOCl	
	Unextracted hydrocarbon mixture	Raffinate	Unextracted hydrocarbon mixture	Raffinate
	Parts	Parts	Parts	Parts
A	356	356	21	1
B	500	500	36	2
C	2,165	2,300	36	1
D	2,315	2,490	58	<1
E	1,895	1,845	118	6
F	1,756	1,930	51	1
G	1,135	1,310	37	4

The decanted liquid portions of the reaction mixtures were each introduced into a reaction vessel with an aqueous solution containing a mixture of sodium bisulfite and sodium sulfite in a molar ratio of 1:5, prepared by dissolving 416 parts (4 mols) of sodium bisulfite (NaHSO_3) and 177 parts (1.67 mols) of sodium carbonate in 1260 parts (70 mols) of water and 180 parts (3 mols) of isopropyl alcohol. The mixtures were agitated and boiled under reflux at a temperature of about

86° for about 4 hours in the case of the nitrosation mixtures identified as A and B, and about 16 hours in the case of the other nitrosation mixtures (because of the relatively low concentration of the olefin addition products in the latter nitrosation mixtures). The sulfitation reaction mixtures were cooled and allowed to separate into an oily layer comprising mainly unreacted hydrocarbons, and an aqueous layer containing surface-active sulfitation products together with a minor proportion of the hydrocarbon fraction, emulsified and dissolved therein. The aqueous layers were separated from the hydrocarbon layers and the pH of the former was adjusted to 7.5 to 8.5 by addition of concentrated aqueous caustic soda or concentrated sulfuric acid, as required. The emulsified hydrocarbons were removed by extraction of the aqueous emulsions at 40° to 50° with a heptane fraction of petroleum in an amount equal to about twice the volume of aqueous emulsion to be extracted. Isopropyl alcohol was removed from the extracted aqueous solutions by distillation. The composition of the aqueous solutions was adjusted by addition of suitable quantities of sodium sulfate or sodium sulfite, to yield on evaporation to dryness, a mixture containing 17.5% carbon in the form of organic compounds, and the solutions were then evaporated to dryness on a drum drier, e. g., at about 100° at atmospheric pressure.

In order to determine the effect of the extraction, the color, i. e., the relative depth of color, of each of the compositions, was determined as follows: A sample of each of the dried compositions was dissolved in water to form a solution of known concentration, and a series of solutions of a commercial sulfonate detergent having a range of known concentrations were prepared. A layer of predetermined thickness of the test sample solution was matched, by visual observation of light transmitted from a given source, against corresponding layers of the series of standard detergent solutions. The reciprocal of the ratio of the concentration of the test sample solution to that of the matching standard sample was taken as the numerical index of relative depth of color of the detergent to be tested. In effect, this numerical index is proportional to the coefficient of light absorption of the detergent tested, or its relative light absorptive power in units of a scale on which the sulfonate detergent had a corresponding light absorption power of 1. The following results, expressed in units of said scale, were obtained:

Hydrocarbon Fraction	I. Light Absorption of sample prepared without preliminary Furfural Extraction	II. Light Absorption of sample prepared with preliminary Furfural Extraction	Ratio I:II
A	3.6	0.33	11:1
B	3.3	0.55	6:1
C	2.6	0.33	8:1
D	2.5	0.45	5.5:1
E	12.5	1.5	8.3:1
F	6.0	0.7	8.6:1
G	4.5	0.77	5.8:1

A comparison of the surface-active properties of the compositions obtained from the original hydrocarbon fractions, and from the corresponding raffinates in aqueous solution (i. e., the washing and wetting properties), indicated no substantial or consistent increase or decrease as a result of the preliminary extraction step.

Upon changing the amount of furfural from 3

parts to 0.5 part per part of hydrocarbon mixture in the extraction procedure as applied to hydrocarbon mixtures A, D, F and G, the decrease in color due to the extraction was found to be much less in each case. Thus the ratios of the color values or indices corresponding to those given in the last column of the preceding table were:

A	4.7:1	10
D	2.1:1	15
F	3.2:1	20
G	1.8:1	25

Thus, it was observed that the decrease in color was about $\frac{1}{3}$ to about $\frac{2}{5}$ as much as that obtained when 3 parts of furfural were employed in the extraction.

On the other hand, upon increasing the proportion of furfural from 3 to 6 parts for each part of hydrocarbon mixture in the case of mixtures A, B, C and G, the improvement in color was relatively insignificant. The values for relative depth of color or light absorptive power (in terms of units of the same scale as that employed above) obtained by use of 6 parts of furfural, and the corresponding values obtained with 3 parts furfural, per part of hydrocarbon mixture in the preliminary extraction step were as follows:

	Extraction with 6 parts of furfural	Extraction with 3 parts of furfural
A	0.23	0.33
B	0.60	0.55
C	0.30	0.33
G	0.55	0.77

Example 2.—1 part of a cracked petrolatum fraction

$$(d_{20}^{20} = 0.8441)$$

composed of hydrocarbons containing 14 to 23 carbon atoms and having an average carbon content of 17.5 carbon atoms per molecule of olefin, said fraction containing the molecular equivalent of 72 per cent of mono-olefins, was extracted at 30° with 10 successive portions of methyl Cellosolve (i. e., ethylene glycol monomethyl ether) using an equal weight of solvent in the first extraction, and in each of the following extractions, a weight of solvent equal to the weight of the raffinate phase obtained from the preceding extraction. After separating the solvent-extract phase from the raffinate phase in the final extraction step, the methyl Cellosolve was removed from the raffinate by distillation. Equivalent quantities of the original hydrocarbon mixture, and of the raffinate residue, which consisted of an olefinic mixture of hydrocarbons

$$(d_{20}^{20} = 0.8171)$$

containing the molecular equivalent of 71.5% of mono-olefins, were reacted with nitrosyl chloride, employing 2.5 to 3 mols of NOCl per mol equivalent of mono-olefin in the respective hydrocarbon mixtures. The insoluble gum resulting from the nitrosyl chloride treatment was separated from each mixture, and the clarified liquid reaction products were heated with aqueous sodium sulfite solutions containing minor proportions of sodium bisulfite and isopropyl alcohol as described in Example 1 employing similar molecular proportions based on the mol equivalents of mono-olefin originally present. After working up the sulfitation mixtures as described in Example 1, the final products, obtained in a dry form, were

tested as in Example 1 for relative light absorptive power (depth of color). The product obtained from the unextracted hydrocarbon mixture had a light absorptive power of 2.2, while the product obtained from the raffinate had a light absorptive power of 0.61, the ratio being 3.6:1. The amount of gum deposited during the nitrosyl chloride treatment of the original hydrocarbon mixture and of the raffinate was in the ratio of 15:1.

Example 3.—A surface-active composition was prepared from the cracked petrolatum fraction of Example 2 by a procedure similar to that of Example 2, except that the extraction with methyl Cellosolve was carried out at 50° instead of at 30°. The relative amount of gum deposited as a result of the nitrosyl chloride reaction was the same as in Example 2. The depth of color of the product in terms of units of the scale used in the foregoing examples was 0.45 as compared with 0.61 for the product of Example 2. Thus the ratio of the respective depth of color values of the products obtained from the unextracted and extracted hydrocarbon mixture was 4.9:1.

Example 4.—1 part of a cracked petrolatum fraction composed of hydrocarbons containing 14 to 23 carbon atoms and comprising the molecular equivalent of 68.5% of mono-olefins, was extracted at 30° with 10 successive portions of liquid sulfur dioxide in a closed extraction apparatus at a gauge pressure of 50 to 52 lbs. per square inch using an equal weight of the solvent in the first extraction and in each of the following extractions, a weight of solvent equal to the weight of the raffinate phase obtained from the preceding extraction. After separating the solvent extract phase from the raffinate phase in the final extraction step, the sulfur dioxide was removed from the raffinate by distillation. Equivalent quantities of the original hydrocarbon mixture and of the raffinate residue, which consisted of an olefinic hydrocarbon mixture

$$(d_{20}^{20} = 0.8150)$$

containing the molecular equivalent of 62.0% of mono-olefins, were reacted with nitrosyl chloride employing 2.5 to 3 mols of NOCl per mol equivalent of mono-olefin in the respective hydrocarbon mixtures. The insoluble gum resulting from the nitrosyl chloride treatment was separated from each mixture and the clarified liquid reaction products were reacted with aqueous sodium sulfite in the manner described in Example 2. The ratio of the gum deposited in the nitrosyl chloride reaction in the case of unextracted hydrocarbon mixture to that deposited from the raffinate was about 85:1. The sulfite reaction product obtained from the unextracted hydrocarbon mixture had a light absorptive power of 4, while the product obtained from the raffinate had a light absorptive power of 0.5, the ratio being 8:1.

In each of the foregoing examples, the extract phase can be fractionated by distillation to recover the extractant solvent, and the hydrocarbon mixture contained therein can be treated in the same manner as the raffinate fraction with nitrosyl chloride and an aqueous solution of sodium sulfite. Highly colored nitrosation-sulfitation products are obtained in each case possessing valuable surface-active properties. The aforesaid extract can also be converted into valuable surface-active sulfonates by direct sulfonation with sulfuric acid and related sulfonating agents.

It will be realized that numerous variations and modifications of the procedure hereinbefore described and illustrated can be made without de-

parting from the scope of the invention. For example, the nitrosation can be carried out in the presence of an alkali metal carbonate as disclosed in copending application Serial No. 424,944, filed December 30, 1941, Patent No. 2,371,418, or in the presence of nitrogen tetroxide or nitrogen trioxide as disclosed in copending application Serial No. 427,345, filed January 19, 1942, of H. A. Beekhuis, Jr., Patent No. 2,370,513. Or, if desired, the olefin mixture can be nitrosated with nitrogen tetroxide or nitrogen trioxide or a mixture thereof, as disclosed in U. S. P. 2,313,719. The sulfitation reaction can be carried out at temperatures initially below 50° C. and completed at temperatures above 65° according to copending application Serial No. 424,943, filed December 30, 1941, Patent No. 2,343,362. The molecular proportion of bisulfite to normal sulfite employed in the sulfitation reaction is advantageously adjusted to 1:5 in accordance with the disclosure of copending application Serial No. 424,941, filed December 30, 1941, Patent No. 2,373,643. The separation of the unreacted hydrocarbons from the aqueous portion of the sulfitation reaction mixture can be facilitated by the use, during the extraction of such hydrocarbons with naphtha, of an emulsion breaker in accordance with the disclosure of copending application Serial No. 427,321, filed January 19, 1942, of W. A. Fessler, Patent No. 2,383,120.

The extraction, according to the present invention, can be carried out in any apparatus adapted to establish intimate contact in an extraction zone between the extraction solvent and the olefinic hydrocarbon mixture to be extracted, and arranged to effect separation of the solvent extract from the purified hydrocarbon mixture or raffinate. It is advantageous to employ an apparatus operating on the countercurrent principle, for instance a packed column in which the solvent and hydrocarbon mixture are introduced at remote points and flow in intimate countercurrent contact, finally separating in the form of a solvent-extract phase and a raffinate phase at opposite ends of the apparatus.

It has been proposed heretofore to carry out the extraction of petroleum oils with selective solvents in such a manner that certain portions of the hydrocarbons dissolved in the extract are liberated, for instance by cooling the extract, the liberated oils being returned to the extraction system. Such modifications in the extraction according to this invention have been found to improve the yield in some cases, but in general this is accompanied by less efficient removal of the chromogenetic hydrocarbon constituents so that the surface-active compositions obtained therefrom are of darker color.

Accordingly, it is preferred to employ a simple countercurrent extraction rather than the aforesaid modification, in order to obtain the desired improvement in color most economically. For this purpose a packed tower may be advantageously employed containing granular, and preferably porous material (e. g., 3 to 4 mesh crushed red brick) as packing. When using a solvent heavier than the hydrocarbon mixture, the hydrocarbon mixture to be extracted is introduced at the base of the tower and the extracting solvent at the top, in the desired rate ratio. The solvent and hydrocarbon mixture flow through the tower in countercurrent relation by gravity forming a solvent-extract phase which accumulates at the base of the tower and a hydrocarbon raffinate phase which accumulates at the top of the tower. The

relative rate of removal of the extract phase is preferably controlled so that the hydrocarbon-solvent interface moves toward the base of the column. Under these conditions, the hydrocarbon mixture constitutes the continuous phase through which the solvent descends in the form of droplets or as a film on the surface of the packing. The extended surface presented by the packing thus tends to insure intimate contact between the two phases. If desired, two or more extraction towers may be operated in series. For example, the solvent may be admitted at the top of the first tower, while the solvent extract leaving the base of each tower is pumped to the top of the next tower until finally recovered from the last tower in the series. Meanwhile, the hydrocarbon mixture is introduced into the base of the last tower and the raffinate issuing from the top of each tower is permitted to flow into the base of the next tower of the series in reverse order until it is recovered from the top of the first tower.

Accordingly, the details of the foregoing examples should be interpreted as illustrative rather than in a limiting sense.

We claim:

1. In a process for preparing surface-active agents by successively reacting a hydrocarbon mixture containing olefinic hydrocarbons and derived from a mineral source with a nitrosating agent and an aqueous solution of a water-soluble sulfite, the improvement which comprises removing chromogenetic constituents of an olefin-containing hydrocarbon mixture of the aforesaid type composed mainly of hydrocarbons containing 10 to 30 carbon atoms, by extracting one part by weight of said hydrocarbon mixture with 0.5 to 6 parts by weight of an extracting agent which is incompletely miscible with said hydrocarbon mixture, which has greater dissolving power for the oxygen-containing, sulfur-containing, nitrogen-containing and aromatic constituents of cracked petroleum than for the paraffins and cycloparaffins of cracked petroleum, and which is a member of the group consisting of methyl lactate, methyl formate, diethylene glycol, furfuryl alcohol, ethanolamine, diethanolamine, ethylene chlorhydrin, beta-beta'-dichlorodethyl ether, ethylene glycol monomethyl ether, furfural, phenol, cresol, nitro-methane, nitro-benzene, morpholine, pyridine, methylamine, ethylene diamine and sulfur dioxide, under temperature and pressure conditions at which the extracting agent is in the liquid phase, separating the solvent-extract phase from the raffinate phase, and reacting olefins contained in the raffinate phase with the nitrosating agent.
2. In a process for preparing surface-active agents by successively reacting a hydrocarbon mixture containing olefinic hydrocarbons and derived from a mineral source with a nitrosyl halide and an aqueous solution of a water-soluble sulfite, the improvement which comprises removing chromogenetic constituents of an olefin-containing hydrocarbon mixture of the aforesaid type composed mainly of hydrocarbons containing 14 to 23 carbon atoms, by extracting one part by weight of said hydrocarbon mixture with 0.5 to 6 parts by weight of an extracting agent which is incompletely miscible with said hydrocarbon mixture, which has greater dissolving power for the oxygen-containing, sulfur-containing, nitrogen-containing and aromatic constituents of cracked petroleum than for the paraffins and cycloparaffins of cracked petroleum, and which is a member of the group consisting of methyl

lactate, methyl formate, diethylene glycol, furfuryl alcohol, ethanolamine, diethanolamine, ethylene chlorohydrin, beta-beta'-dichloroethyl ether, ethylene glycol monomethyl ether, furfural, phenol, cresol, nitro-methane, nitro-benzene, morpholine, pyridine, methylamine, ethylene diamine and sulfur dioxide, under temperature and pressure conditions at which the extracting agent is in the liquid phase, separating the solvent-extract phase from the raffinate phase, and reacting olefins contained in the raffinate phase with the nitrosating agent.

3. In a process for preparing surface-active agents by successively reacting a hydrocarbon mixture containing olefinic hydrocarbons and derived from a mineral source with a nitrosyl halide and an aqueous solution of a water-soluble sulfite, the improvement which comprises removing chromogenetic constituents of an olefin-containing hydrocarbon mixture of the aforesaid type composed mainly of hydrocarbons containing 14 to 23 carbon atoms, by extracting 1 part by weight of said hydrocarbon mixture with 0.5 to 6 parts by weight of furfural at 0° to 70° C., separating the solvent-extract phase from the raffinate phase, and reacting olefins contained in the raffinate phase with the nitrosyl halide.

4. In a process for preparing surface-active agents by successively reacting a hydrocarbon mixture containing olefinic hydrocarbons and derived from a mineral source with a nitrosyl halide and an aqueous solution of a water-soluble sulfite, the improvement which comprises removing chromogenetic constituents of an olefin-containing hydrocarbon mixture of the aforesaid type composed mainly of hydrocarbon containing 14 to 23 carbon atoms, by extracting 1 part by weight of said hydrocarbon mixture with 0.5 to 6 parts by weight of liquid sulfur dioxide at a temperature below 50° C. under superatmospheric pressure, separating the solvent-extract phase from the raffinate phase, and reacting olefins contained in the raffinate phase with the nitrosyl halide.

5. In a process for preparing surface-active agents by successively reacting a petroleum fraction containing olefinic hydrocarbons with nitrosyl chloride and an aqueous solution of a water-soluble sulfite, the improvement which comprises removing chromogenetic constituents of an olefin-containing petroleum fraction composed mainly of hydrocarbons containing 14 to 23 carbon atoms, by extracting said petroleum fraction with 2.5 to 5 parts by weight of substantially moisture-free furfural, per part by weight of the petroleum fraction, at 25° to 50° C., separating the solvent-

extract phase from the raffinate phase, and reacting olefins contained in the raffinate phase with nitrosyl chloride.

6. In a process for preparing surface-active agents by successively reacting a hydrocarbon mixture containing olefinic hydrocarbons and derived from a mineral source with a nitrosyl halide and an aqueous solution of a water-soluble sulfite, the improvement which comprises removing chromogenetic constituents of an olefin-containing hydrocarbon mixture of the aforesaid type composed mainly of hydrocarbons containing 14 to 23 carbon atoms, by extracting one part by weight of said hydrocarbon mixture with 0.5 to 6 parts by weight of ethylene glycol monomethyl ether at 0° to 70° C., separating the solvent-extract phase from the raffinate phase, and reacting olefins contained in the raffinate phase with the nitrosyl halide.

10 7. In a process for preparing surface-active agents by successively reacting a petroleum fraction containing olefinic hydrocarbons with nitrosyl chloride and an aqueous solution of a water-soluble sulfite, the improvement which comprises removing chromogenetic constituents of an olefin-containing petroleum fraction composed mainly of hydrocarbons containing 14 to 23 carbon atoms, by extracting said petroleum fraction with 2.5 to 5 parts by weight of substantially

15 moisture-free ethylene glycol monomethyl ether, per part by weight of the petroleum fraction, at 25° to 50° C., separating the solvent-extract phase from the raffinate phase, and reacting olefins contained in the raffinate phase with nitrosyl chloride.

20 8. In a process for preparing surface-active agents by successively reacting a petroleum fraction containing olefinic hydrocarbons with nitrosyl chloride and an aqueous solution of a water-soluble sulfite, the improvement which comprises removing chromogenetic constituents of an olefin-containing petroleum fraction composed mainly of hydrocarbons containing 14 to 23 carbon atoms, by extracting said petroleum fraction with 2.5 to 5 parts by weight of substantially

25 moisture-free ethylene glycol monomethyl ether, per part by weight of the petroleum fraction, at 25° to 50° C., separating the solvent-extract phase from the raffinate phase, and reacting olefins contained in the raffinate phase with nitrosyl chloride.

30 9. In a process for preparing surface-active agents by successively reacting a petroleum fraction containing olefinic hydrocarbons with nitrosyl chloride and an aqueous solution of a water-soluble sulfite, the improvement which comprises removing chromogenetic constituents of an olefin-containing petroleum fraction composed mainly of hydrocarbons containing 14 to 23 carbon atoms, by extracting said petroleum fraction with 2.5 to 5 parts by weight of substantially

35 moisture-free ethylene glycol monomethyl ether, per part by weight of the petroleum fraction, at 25° to 50° C., separating the solvent-extract phase from the raffinate phase, and reacting olefins contained in the raffinate phase with nitrosyl chloride.

Certificate of Correction

Patent No. 2,447,308.

August 17, 1948.

LELAND JAMES BECKHAM ET AL.

It is hereby certified that error appears in the printed specification of the above numbered patent requiring correction as follows: Column 13, line 9, for "Patent No. 2,370,513" read *Patent No. 2,370,518*; and that the said Letters Patent should be read with this correction therein that the same may conform to the record of the case in the Patent Office.

Signed and sealed this 26th day of October, A. D. 1948.
